FUSE

Louis J. Molner, Bridgeport, Conn.

Application July 28, 1938, Serial No. 221,659

8 Claims. (Cl. 200—119)

This invention relates to tamper proof devices adapted to prevent a wire or penny being inserted to bridge the contacts in a fuse holder when the fuse is blown.

5 An object of this invention is to provide a tamper-proof device of this type which is simple, of few parts, inexpensive, and has the contacts protected.

Another object is to eliminate the necessity of 10 a threaded metal holder.

A further object is to provide a holder and fuse receptacle in which the contacts are provided for butt engagement, one of them being yieldable to eliminate the necessity for expensive precision 15 constructions.

Referring to the drawing:

Fig. 1 is a longitudinal section through one embodiment of this invention.

Fig. 2 is a top plan view of the stationary support for the fuse receptacle, with parts broken away.

The removable fuse receptacle 10 is supported by a holder comprising a base 11 preferably of porcelain or other appropriate insulating material, having integrally formed therefrom an up-standing generally circular wall 12.

Within wall 12, and substantially concentric thereto, is a knob or projection 13 which may or may not be of the same material as the base and 30 which may or may not be integral therewith. In the drawing this projection 13 is shown as being formed separately from the base. Within the knob or projection, and below the surface thereof, is a central contact 14 constituting one of the contacts with which the fuse receptacle engages. The other contact of the fuse holder is the substantially ring shaped portion 15 extending around the bottom of the projection 13 but within wall 12. This contact ring 15 is bent or raised at 16 and 16a 35 so that the greater part of the ring is adapted to be yieldably engaged by a complementary contact carried by the fuse receptacle. This contact ring is secured to the base by the screw 16b or in any other convenient manner. A terminal binding screw 17 is located on a projection from the contact ring 15 while the opposite terminal screw 18 is located on a conducting strip 19 in contact with the central terminal 14. As shown on the drawing, the lower central portion of the central 40 conducting rod is threaded to receive a nut 20 for clamping the conductor strip 19 in position and at the same time clamping the knob or projection 13 on to the base. The projection 13 is shown in Fig. 1 as being recessed to allow inser-

tion of the nut prior to its being threaded on the central conducting rod.

The fuse receptacle includes a body of cup shaped insulating material having imbedded therein a spherical or other anchoring portion 21 for its central contact which is adapted to engage the central contact 14 of the fuse holder.

The central contact 21 is preferably of carbon and the contact 14 preferably of copper or other good electrical conducting metal. A fusible strip 10 22 extends from the contact 21 radially outward and then longitudinally within a passage 23 in a side wall of the cup, being secured at its lower end portion to a contact ring 24 which engages the contact ring 15. The contact ring 24 is preferably 15 soldered to the fusible strip 22 when not inserted in the cup walls and after being soldered to the fusible strip is then set into the cup walls as shown in Fig. 1, a plurality of pins 25 being used to firmly hold the contact ring 24 in place. As shown in 20 Fig. 1, the pins 25 extend from the cup walls and also through the contact ring 24. Across the opposite end of the cup is placed a sheet of mica or other substantially transparent covering as is customary in fuse receptacles in order 25 that observation may determine whether the fuse has been melted. A clamping band of metal 27 extends around the base of the cup for holding the mica or other transparent material in position.

The inside of the cup walls are threaded for co-operation with corresponding threads on the outside of the projection 13.

The cup 10 of the fuse receptacle may be of the same material as the projection 13 and base, though preferably it is of a molded resinous or 35 phenolic condensation type product. The materials of the projection 13 and cup 10 should be such as to allow smooth and easy threading of the one upon the other.

Among the advantages of this invention may be 40 mentioned its simplicity and few parts. Neither the fuse receptacle nor its holder is apt to be injured by dropping since there is no threaded metal shell. The contacts of both parts are protected and surrounded by insulation so that there is no 45 likelihood of shock and the device is substantially foolproof.

In inserting the fuse receptacle on to the holder the cup is rotated until the contact ring 24 first 50 engages the contact ring 15 and finally the circuit is closed by engagement of the contacts 21 and 14. In opening the circuit the contacts 21 and 14 separate in advance of the contacts 24 and 15. The contact 15 being yieldable takes care of any wear or corrosion in the contacts 21 and 14. 55

I claim:

1. A removable fuse receptacle, a holder therefor comprising a base and an encircling upstanding wall, a second and inner upstanding wall, contacts protected by said walls, at least one of said walls constituting a guide for the removable receptacle, said removable receptacle being a cup-shaped member of insulating material adapted to enclose the inner wall of the holder, contacts in the holder and receptacle adapted for butt engagement. 5
2. A holder for a removable fuse receptacle including inner and outer walls of insulating material, screw threads on the outer surface of the inner wall, a base connecting said walls, a contact ring on the base between said walls, and another contact within the inner wall extending to adjacent its top. 10
3. A removable fuse receptacle including a cup-shaped member of insulating material having screw threads formed on the inner surface of the sides of the cup, a contact in the inner base of the cup, a second contact in the cup walls remote from the base, a strip of fusible material connecting said contacts, and a cover of transparent material across the base of the cup to render the fusible strip visible. 15
4. The combination with a stationary fuse holder, of a removable fuse receptacle of the type adapted to prevent bridging the contacts within the stationary fuse holder, the improvement in said holder and receptacle which includes an upstanding projection of insulating material on said holder and having screw threads on the outer 20 surface thereof, a contact within said projection, a yieldable ring contact on said holder around the base of said projection, the removable receptacle being cup-shaped, provided with threads on the inner surface of the cup walls adapted to cooperate with the threads on said projection, a contact in the base of the cup for engagement with the contact in said projection, and another contact carried by and adjacent an end of the cup walls for engagement with said yieldable ring, and a fuse strip connecting the contacts of the 25 removable receptacle. 30
5. A stationary member with which a fuse receptacle is adapted to contact, said member including a base, terminals on the base, an upstanding wall of insulating material, a knob of insulating material enclosed by the wall, a central contact in said knob, means clamping said knob to the base, a conductor between one of the base terminals and said central contact, said clamping means also holding said conductor and central contact in position. 35
6. A stationary member with which a fuse receptacle is adapted to contact, said member including a base, terminals on the base, an upstanding wall of insulating material, a knob of insulating material enclosed by the wall, a central contact in said knob, a conductor intermediate the top and bottom of said base and connecting said central contact with one of the terminals on the base, a contact ring around the knob, within said wall of insulating material, and connected to another base terminal. 40
7. A stationary member with which a fuse receptacle is adapted to contact, said member including a base, terminals on the base, an upstanding wall of insulating material, a knob of insulating material enclosed by the wall, a central contact in said knob, a conductor intermediate the top and bottom of said base and connecting said central contact with one of the terminals on the base, a contact ring around the knob, within said wall of insulating material, and connected to another base terminal, said ring being bent so as to be yieldable and not lie contiguous the base in all portions thereof while yieldable. 45
8. A fuse receptacle of insulating material in cup form, a central contact embedded in and projecting from the base of said cup, a contact in the end portion of the cup walls, a fusible strip connecting the central and wall contacts and extending in a passage between the inner and outer surfaces of the cup walls, said contact in the end of the cup walls being removable from the cup walls to enable it to be attached to said fusible strip, and means for holding said contact at least partially within the cup walls. 50
